CROCHET-MACHINE TAKE-UP.

1,111,987.

Specification of Letters Patent. Patented Sept. 29, 1914.

Application filed November 15, 1913. Serial No. 801,200.

To all whom it may concern:

Be it known that I, SAMUEL WALTER Avis, a citizen of the United States, residing at Hartford, in the county of Hartford, 5 State of Connecticut, have invented certain new and useful Improvements in Crochet-Machine Take-Ups; and I do hereby declare the following to be a full, clear, and exact description of the same, reference being had 10 to the accompanying drawings, forming a part of this specification, and to the figures and letters of reference thereon.

My invention relates to improvements in crochet or overseaming sewing machines and 15 particularly to that class of machine employing a thread carrying implement for passing a thread through the fabric near its edge, and a coöperating looping implement for drawing thread from the thread carrying implement, above and below the fabric, 20 to the edge of the fabric where the said thread is interlooped.

The general object of the invention is to provide a take up for pulling off and controlling the main thread of crochet machines, or that thread which is passed through the fabric, whereby strains to 25 which the crochet hook and the stitch forming mechanism generally have been subjected are relieved, whereby the thread loops are relaxed as they pass over the hook latch and thus the cutting of the loops is prevented and the excessive wear on the hook latch is diminished, and whereby the formation 30 of the stitch and the manner in which the same is laid is better controlled.

With these and other objects in view, my invention consists in certain new and useful combinations of elements and in the details 40 of construction as hereinafter more fully set forth.

In the drawings: Figure 1 is a front elevation of a crochet machine embodying my invention, the frame cap of which has been 45 removed and a portion of the machine broken away to more clearly disclose the stitch forming mechanism and the stitch being formed. Fig. 3 is an end elevation of the same machine, looking from the left of Fig. 1, the moving parts, however, being in another position. Figs. 2 and 4 are diagrams showing the operation of the take up mechanism.

Like characters of reference throughout 50 the drawings indicate the same parts.

My invention is particularly adapted to use in connection with crochet machines, such as the well known Merrow blanket hemming crochet machine which is of the same general character as the machines disclosed and referred to in United States Patents Nos. 195,520 issued September 25, 1877 to Joseph M. Merrow; 394,782 issued December 18, 1888 to Joseph M. Merrow; 413,761, issued October 29, 1889 to Joseph M. Merrow; 441,315 issued November 25, 1890, to Joseph M. Merrow; which machines produce a finish or edge of the same general character as is disclosed in United States Patent No. 413,531 issued October 22, 1889 to Joseph M. Merrow.

The embodiment of my invention shown in the drawings is a form particularly suited to the usual Merrow blanket hemming machine and this form is adapted to be used 75 either as an attachment to machines already on the market or to be built into new machines.

Referring to the drawings: the numeral 1 indicates the eye pointed needle, 2 the needle bar, 3 the needle bar clamp which is pivotally connected by the screw stud 4 to the link 5 which in turn is pivotally connected by the screw stud 6 to the needle bar lever 7 which is fulcrumed on the stud 7^a and which is connected through the ball joint 7^b to the pitman 8 which embraces the ball eccentric 9 which is secured to the hand wheel 10, or in any way is held in fixed relation with the shaft 11 on which the hand wheel is mounted, whereby the needle is reciprocated.

On the shaft 11, is mounted the cylindrical cam 12 which is provided with a gear 12^a which meshes with a gear 13^a on the cylindrical cam 13 which, is mounted on the shaft 95 or arbor 13^b. The grooves 12^b and 13^b are engaged by the arms 14^a and 14^b of the hook carrier 14 which is pivotally mounted on the carrier block or guide 15 which is constrained vertically by the stationary gib 16 and the adjustable gib 16^a between which the guide reciprocates horizontally in a plane parallel to the axes of the cams. The adjustment of the gib 16^a is effected by means of the wedge 17 and the inclined face 100 18^a of the frame cap 18. The elements 16, 16^a, 17 and 18^a are indicated in Fig. 1 by the dot and dash lines. The hook carrier 14 is further constrained by the angular guide 19 which is adjustably secured to the frame by 11

the screw 19^a. Through this mechanism, the latch hook 20 which is secured to the carrier 14 by the screw 14^c, receives its vibratory reciprocating motion which causes it to cooperate above and below the chaining finger with the needle in the formation of a stitch.

The numeral 30 denotes the feed dog which is secured by the screw 30^a to the bar 31^a of the feed dog carrier 31 which is slidably and pivotally supported at its rear end by the screw stud 32. The rising and falling movements of the feed are imparted by the eccentric 33 and the feeding or fore 15 and aft movements, by the eccentric 34, which is secured to the shaft 11 by the screw 34^a, and the spring 35.

The numeral 40 indicates the work plate, 41 the needle plate, 42 the chaining finger, 20 43 the presser foot which is secured by the screw 43^a to the bar 43^b. The spring 43^c applies the pressure to the presser foot through the lifter 43^d which is secured to the bar 43^b by the screw 43^e. The numeral 25 44 denotes the fabric having the hemmed portion 44^a, 45 the needle guard, 46 the machine frame, which has an overhanging arm 46^a on the end of which is the frame head 46^b provided with the bosses 46^c and 46^d; 30 the numeral 47 indicates the tension and the numeral 48 the hemmer. The machine thus far described is an example of an ordinary Merrow blanket hemming crochet machine.

In the operation of this machine, assuming the needle to have penetrated the fabric and carried the thread with it, and assuming the hook to have advanced under the chaining finger to a point beyond the needle; the hook withdrawing from this position 35 (moving to the right as viewed in Fig. 1), grasps the thread from the needle, as the latter is ascending, in the region of the slabbed portion 1^a (see Fig. 3), and pulls the thread out to the edge of the chaining finger and fabric. The hook then passes up 40 around the edge of the chaining finger and fabric thus forming a loop from beneath the fabric which loop is wrapped around the two edges and the under side of the chaining finger. When the hook has risen sufficiently to clear the fabric it advances over 45 the fabric until its throat 20^b has passed beyond the needle thread. This causes the under loop, just formed, to slip back over 50 the latch 20^c on to the hook shank. The hook then withdraws from this position over 55 the fabric and from the lower loop around its shank, grasps the needle thread from the descending needle while withdrawing, 60 which thread it pulls to the edge of the fabric and chaining finger and through the previous or lower loop, which loop closed the latch as it was shed, and, dropping down sufficiently to clear the under side of the 65 chaining finger, the hook advances toward

the needle under the chaining finger until the hook's throat has passed beyond the needle. This causes the upper loop, just formed, to slip back over the latch on to the shank of the hook. The hook again withdraws, grasps the thread from the needle as the latter is ascending, and pulls the thread to the edge of the chaining finger and fabric, and through the previous or upper loop, which loop closed the latch as 70 it was shed. The hook then, rising sufficiently to clear the chaining finger and the upper side of the fabric, advances over the fabric as before, thus completing a stitch formed from a single thread with two loops 75 80 at the edge of the fabric while the thread passes through the fabric but once, as is shown in United States Patent No. 413,531 hereinabove referred to.

The feed in these machines occurs each 85 time the needle emerges from the fabric. Inasmuch as two loops are formed, in the above described machine, for each complete operation of the needle it has been found to be desirable to provide the machine with 90 a take up and pull off, operating for each loop or twice for each complete set of stitches, whereby the pulling off and control of the thread may be effected as required. 95

By the use of my invention, the stitch forming implements are relieved of much of the pull off or take up strains, the stitch loops are controlled and their passage over and back of the hook latch is facilitated, 100 and the point at which the interlooping occurs along the edge of the fabric may be better regulated.

Referring more particularly to the embodiment of my invention illustrated and shown applied in the drawings: the numeral 50 indicates the take up frame which is provided with the webs 50^a and 50^b and the ears 50^c and 50^d which are counterbored at 50^e and 50^f to a depth required to bring the frame 50 in central alinement with the path of reciprocation of the eye 60 which eye will be further described. The frame 50 is secured to the machine by the shoultered tension stud 51 and the headed stud 52 which hold the counterbored faces 50^e and 50^f to the inner faces of the bosses 46^c and 46^d respectively, the shanks 51^a and 52^a of the studs 51 and 52 are securely held in the bosses 46^c and 46^d respectively by the screw 53 and the screw stud 54 which latter also acts as a thread guide. 110

The stationary adjustable thread eyes or eye pieces 55 and 56 are secured by the screws 57 and 58 (which are threaded into suitable holes 50^g in the frame 50), to the faces 50^h and 50ⁱ of the frame 50. The webs 50^a and 50^b effectively prevent the eye pieces 55 and 56 from turning on the screws 57 and 58 and the adjustment of the eye pieces 55 120 125 130

and 56 is provided by the slots 55^a and 56^a, through which the screws pass, and the three holes 50^c into any of which the screws may be placed. When still further adjustment is desired, the eye pieces 55 and 56 may be reversed, that is, the eye 55 for instance, may be turned with the portion through which the eye 55^b passes, up and its screw passed through the slot 55^a from 10 its other side, thus securing the face of the eye that is now shown outside, to the face 50^a of the frame 50; by thus reversing the eyes and by the use of the holes 50^c, which may be more numerous if desired, the range 15 of adjustment of either eye may consist of the entire distance between the bosses 46^c and 46^a.

The reciprocating thread eye 60 is mounted on the screw stud 4 by a shank which fits 20 into a bore in the stud 4 and which shank is secured to the stud by the screw 61 in the same manner as is set forth in an application of Joseph M. Merrow, filed in the United States Patent Office January 9, 1913, 25 and bearing Serial No. 741,060.

In the operation of my invention when applied to a machine as shown: when the needle descends and passes through the fabric, it carries with it a loop of thread 30 and, just before the end of the stroke, the eye 60 passing between the eyes 55^b and 56^b pulls off a slight amount of thread as shown in Fig. 4. As the needle ascends, the hook pulls the thread passed through the fabric 35 by the needle, out to the edge into a loop, in the meantime, the eye 60, ascending with the needle, prepares to relax or pay off the thread that it has pulled off which relaxing it does as it passes through the position 40 shown in Fig. 1, at which time the hook has about finished pulling out the lower loop and thus the thread that the eye 60 pays off serves to slacken the loop just formed, so that the hook may readily pass its latch and 45 shank through the said loop on its way over the fabric.

As the needle continues its ascent from the position shown in the Fig. 1, the eye 60 passing upward through between the eyes 55^b and 56^b pulls off a comparatively large amount of thread as shown in Fig. 2, since the needle on its ascending stroke pulls off little or no thread and the eye 60 must therefore pull off all the thread needed both 55 for forming the stitch and for easing off the stitch. This pull off action of the eye 60 also takes up the slack in the thread system and sets the last formed stitch. When the needle descends from the position shown 60 in Fig. 2, the eye 60 as it approaches the position shown in the Fig. 1 pays off thread to the hook as the said hook forms the upper loop, drawing the same through the lower loop which it is shedding, and, when the 65 implements have assumed the positions

shown in Fig. 1, the hook has ceased to draw thread and is beginning to advance under the chaining finger thus passing its latch through the loop just drawn, which the paying off action of the eye 60 has caused 70 to be left slack around the hook shank to facilitate the passage of the latter therethrough. The needle on continuing its descent through the fabric passes a loop of thread through the fabric as before, and the eye 60, continuing its descent and passing between the eyes 55^b and 56^b as before, sets 75 the stitch just formed and pulls off a slight amount of thread as and for the purposes above explained. 80

The adjustment in which this device is shown and in which adjustment the operation of the said device has been explained, is an adjustment in which the enchainment 85 of the loops is supposed to be laid along the center of the edge of the fabric and has merely been selected as a typical case. This take up and the adjustments thereof hereinabove described, have been found to be desirable for obtaining improved results on 90 fabrics of various thickness and on finishes of different widths.

Having thus described my invention, what I claim and desire to secure by Letters Patent of the United States is:

1. In a machine of the class described, a take up consisting in the combination of a take up frame, means including a pair of ears on the said frame for securing the same to the machine, and a pair of eye pieces 100 mounted on the take up frame, the said eye pieces being each provided with a laterally extending eye portion, with a reciprocating thread eye member coöperating with the eye portions of the eye pieces whereby the thread 105 is pulled off and taken up twice during the formation of a double loop stitch.

2. In a double loop stitch crochet machine, a take up consisting in the combination of a take up frame secured to the machine by means including a pair of laterally extending ears, a pair of eye pieces mounted on the said frame and disposed one on either side of the path of a coöperating reciprocating thread eye member, whereby the thread 110 is pulled off and taken up twice during the formation of each double loop crochet stitch.

3. In combination in a double loop stitch crochet machine a take up comprising a frame provided with a pair of longitudinally extending webs disposed one on either side of the said frame, means for securing the frame to the machine, a pair of eye pieces adjustable in the direction of the length of the said webs, each of the said eye pieces having a portion for engaging one of the said webs, means for adjustably securing the eye pieces to the frame and, a reciprocating thread eye member coöperating 120 with the eye pieces whereby the thread 125 is pulled off and taken up twice during the formation of each double loop stitch.

is pulled off and taken up twice during the formation of a double loop crochet stitch.

4. In combination in a crochet machine including a stitch forming mechanism and a reciprocating thread eye member actuated thereby, a take up comprising a take up frame having a pair of oppositely disposed webs extending in the direction of the path of the reciprocating thread eye member, means for securing the frame to the machine, a pair of stationary eye pieces adjustable in the direction of the length of the frame webs, each of the said eye pieces having a portion for engaging one of the said webs, means for adjustably securing the eye pieces to the frame and in contact with the webs thereof, whereby the eye pieces may coöperate with the reciprocating thread eye member to effect the pulling off and taking up of the thread.

5. In a machine of the class described, a take up consisting in the combination of a take up frame, a web projecting from each of the two sides thereof, a plurality of screw holes arranged in the frame with their axes in a plane parallel to the plane of the webs, means for securing the frame to the machine, a pair of adjustable eye pieces each having a screw slot for registering with the screw holes in the frame and a surface, parallel with the side of the slot adjacent thereto, for engaging one of the frame webs, and a reciprocating thread engaging implement coöperating with the eye pieces to pull off, take up and control the thread.

6. In combination in a crochet machine including a stitch forming mechanism and a reciprocating thread eye member actuated thereby, a take up comprising a take up frame secured to the machine in the direction of the path of the reciprocating thread eye member, a pair of reversible eye pieces adjustable longitudinally with relation to the frame and the path of the reciprocating eye member, the said eye pieces having eye portions projecting therefrom toward the plane generated by the axis of the eye of the reciprocating eye member, and means

for adjustably securing the eye pieces to the frame; whereby the eye pieces may coöperate with the reciprocating thread eye member to effect the pulling off, taking up and control of the thread.

7. In combination in a crochet machine including a stitch forming mechanism and a reciprocating thread eye member actuated thereby, a take up comprising a take up frame, means for securing the frame to the machine, a pair of reversible stationary thread eye pieces coöoperating with the reciprocating thread eye member and adjustable in a line parallel to the path of the said reciprocating eye member, each eye piece being provided with a slotted portion and clamping means whereby the said eye piece is secured to the frame, and means for guiding and constraining the eye pieces.

8. In combination in a crochet machine, a take up including a take up frame, means, including a plain headed stud and a sholdered and shanked tension stud, whereby the said frame is secured to the machine; a pair of eye pieces, adjustably secured one to each side of the frame, and a reciprocating thread eye member coöperating with the eye pieces and operating in a path therebetween, whereby the thread is pulled off taken up and controlled during the formation of a stitch.

9. As an attachment to a crochet machine, a take up comprising the frame 50 having the webs 50^a and 50^b, the holes 50^c, the ears 50^e and 50^d, and the studs 51 and 52 for securing the said frame to the machine; in combination with the eye pieces 55 and 56, each having an eye portion, a slot and a web 85 engaging portion, and an eye member 60, provided with suitable means for securing the same to a moving member of the machine and, coöperating with the eyes 55^b and 56^b; substantially as shown and described.
